CLAIM

The ornamental design for a bird cage cover, as shown and described.

DESCRIPTION

FIG. 1 is a front perspective view of a bird cage cover with a front panel lifted showing my new design;

FIG. 2 is a front view thereof with a front panel down;

FIG. 3 is a rear view thereof;

FIG. 4 is a top view thereof;

FIG. 5 is a bottom view thereof;

FIG. 6 is an end view thereof; and,

FIG. 7 is an opposite end view thereof.

The broken line showing of the bird cage in FIG. 1 is for illustrative purposes only and forms no part of the claimed design.
